UNITED STATES PATENT OFFICE.

WILLIAM N. WHITELEY AND WILLIAM BAYLEY, OF SPRINGFIELD, OHIO,
ASSIGNORS TO SAID WHITELEY.

KNOTTING DEVICE FOR GRAIN-BINDERS.

SPECIFICATION forming part of Letters Patent No. 415,756, dated November 26, 1889.

Application filed October 13, 1886. Serial No. 216,090. (No model.)

To all whom it may concern:

Be it known that we, WILLIAM N. WHITELEY and WILLIAM BAYLEY, citizens of the United States, residing at Springfield, in the county of Clark and State of Ohio, have invented certain new and useful Improvements in Knotting Devices for Grain-Binders; and we hereby declare the following to be such a full, clear, and exact description of the invention as will enable any person skilled in the art to which it pertains to construct and use the same, reference being had to the accompanying drawings, forming a part of this specification.

Our invention relates to knotting devices for grain-binders in general and particularly to those constructed upon the general principles set forth in Letters Patent No. 212,420, granted February 18, 1879, to J. F. Appleby, and is in the nature of improvements thereon.

The objects of our invention are to simplify the mechanism by which the cord-holder disk is actuated and at the same time to obviate certain defects in the operation of the knotting devices used upon the class of grain-binders to which our invention is applicable, and to so construct and arrange the parts by which the cord-holder disk is actuated that its movements may rotate it promptly and positively when required and hold it securely at rest at all other times. These objects are accomplished by means of the mechanism shown in the accompanying drawings and hereinafter described.

In the drawings, Figure 1 is a perspective view of such parts of a "knotter" as are necessary to clearly illustrate our invention. Fig. 2 is a vertical section of the same with some of the parts shown in elevation. Fig. 3 is a side elevation of the cord-holder and cord-holder disk, and Fig. 4 is a longitudinal section of a modification of the method of pivoting the swinging frame to the main frame.

Similar letters refer to like parts in the several views.

A is the knotter-frame, having formed on it two horizontally-perforated lugs or projections *a a*, to which the swinging cord-holder frame B is pivoted by the shaft E, which transmits power from the tyer-wheel C to the cord-holder disk K. The binder-shaft *m* and

tyer-wheel C are arranged as usual, the latter being provided, however, with a segment of an internal gear having formed thereon the teeth *c*, which engage those of the mutilated pinion D, which is provided with two flat spaces *d d*, which fit the inner surface of the delay-rim *g*. The number of teeth *c* and of teeth on each side of the pinion D are the same, whereby the pinion D makes only one-half of a revolution to one revolution of the tyer-wheel, the lugs *h h*, formed upon pinion D, being engaged by the pin *p*, fixed in the delay-rim *g*, for starting the pinion D positively and causing the teeth to properly engage in the usual manner in such cases.

Upon the shaft E is fixed the bevel-pinion F, engaging the bevel-wheel G, which is fixed to the shaft M, journaled in the swinging cord-holder frame B and having fixed to its lower end the bevel-pinion H, which engages the bevel-pinion T, fixed to the shaft J, journaled in the swinging frame B and having fixed to its front end the cord-holder disk K.

The cord-holder disk K has six cord-notches formed therein, and must be so actuated that one of the notches shall arrive at the cord-holder L at each knot formed. To accomplish this the pinion D is caused to make one-half of a revolution to every revolution of the tyer-wheel. The bevel-pinion F has one-third as many teeth as the bevel-wheel G. Consequently the shaft M makes one revolution to six revolutions of the tyer-wheel, and the bevel-pinions H T being of equal diameters, the cord-holder disk K rotates one-sixth of a revolution, or from one cord-notch to the next, at each revolution of the tyer-wheel.

The cord-holder L is of the usual construction, and is pivoted to the swinging frame B at *l* and held in place, as usual, by the spring N, attached to the projection *b* of the swinging frame B.

The cord-holder and cord-holder disk are shown in detail at Fig. 3.

The bill-hook R is of the usual construction, and has fixed to it the bill-hook pinion *r*, which engages the teeth *j* of the tyer-wheel, by which it is rotated in the usual manner.

The cord-holding apparatus is mounted upon the swinging frame B for the purpose

of allowing the cord-holder to swing up to the bill-hook while the latter rotates, in order to supply slack cord for properly forming the knot. To accomplish this the swinging frame 5 B has formed on it the arm e, which carries the friction-roller f, which engages the cam P, formed on the tyer-wheel, and by which the cord-holding apparatus is caused to swing backward away from the bill-hook, and by a 10 depression in said cam the swinging frame B is allowed to swing inward toward the bill-hook R, as described. When the swinging frame B is caused to swing outward by the 15 action of the cam P, it is arrested at the proper point by the stop-lug b², formed upon it, coming in contact with the frame A at a².

The cam P may be constructed of two tracks or rims, the friction-roller f being situated between them, thus insuring a positive 20 swinging motion to the cord-holding apparatus; but in practice it is found that the pulling of the cord as the bill-hook rotates in forming the knot is quite sufficient, and a much more natural movement in cases where 25 the cord varies much in the size, &c.

In Figs. 1 and 2 we have shown the swinging frame B pivoted to the lugs a a of the main frame A by the shaft E; but it may be preferable to form the bearing for the swinging 30 frame B upon projecting sleeves formed upon the lugs a a, as shown in Fig. 4, and confined thereon by a nut V or other similar means. The shaft E passing through the stationary lugs a a is not then interfered 35 with or cramped by the swinging frame B.

The operation of our invention is as follows, viz: The needle-arm S, encircling the gavel with the binding-cord, lays the latter over the bill-hook and into one of the notches 40 k of the cord-holder disk, as shown. The tyer-wheel then rotating in direction of the arrow, the teeth c, formed thereon, engage those of the pinion D, which, operating through the shaft E, gears F G, shaft M, and gears H 45 T, rotate the cord-holder disk K one notch, thus forcing the cord down to the position of the notch k², Fig. 3, at which time the teeth c of the tyer-wheel and those of the pinion D disengage, and the delay-rim g coming in 50 contact with one of the flat surfaces d of the pinion D the latter is locked and consequently the cord-holder disk K held at rest. The bill-hook is now rotated by the teeth j of the tyer-wheel engaging the teeth of the 55 bill-hook pinion r. At the same time the

depression in the cam P comes opposite the friction-roller f of the arm e, and the cord-holding apparatus is allowed by the pulling of the binding-cord to swing inward toward the bill-hook to the position shown by dotted 60 lines in Fig. 2, thus furnishing slack cord for the formation of the knot, after which the cord being severed by any convenient device the cam P causes the swinging frame and cord-holding apparatus to swing outward 65 to its original position, where it is arrested by the stop-lug b² coming in contact with the frame A at a².

We are aware that knotters have heretofore been constructed in which the cord-holder disk was actuated by means of spur and bevel gears transmitting the power from the tyer-wheel or binder-shaft, but in all such cases the cord-holder disk was journaled to the main frame or some fixed part 70 thereof; but in our invention we have so constructed the parts that the cord-holder and cord-holder disk may be mounted upon a swinging frame, the said frame swinging 75 forward for the purpose of furnishing slack 80 cord to the bill-hook in forming the knot, as in practice this feature has been found necessary to prevent too great a strain on the cord, which frequently caused the accidental breaking thereof.

Having thus described the nature, objects, construction, and use of our invention and pointed out wherein it differs from the usual forms now made, what we claim as new, and desire to secure by Letters Patent, is— 85

In a knotting device for a grain-binder, the combination of a fixed frame having the knotting-hook journaled therein, a wheel on the tyer-wheel shaft, provided with a segment-gear c, a shaft E, journaled in brackets on 90 said fixed frame and provided with a spur-gear D in mesh with said segment-gear and a bevel-gear F, a swinging frame pivoted on said shaft E, a rotary cord-holder having a bevel-gear, countershaft-connection with said gear F, mounted on said swinging frame, and automatic means to swing said swinging frame on its axis coincident with the axis of the driving-shaft E. 100
